UNITED STATES PATENT OFFICE.

WILLIAM SCHAEFER, OF WATERVILLE, CONNECTICUT, ASSIGNOR TO BERBECKER & ROWLAND MANUFACTURING COMPANY, OF WATERVILLE, CONNECTICUT, A CORPORATION OF CONNECTICUT.

CURTAIN ROD.

Application filed January 12, 1923. Serial No. 612,160.

To all whom it may concern:

Be it known that I, WILLIAM SCHAEFER, a citizen of the United States, residing in Waterville, in the county of New Haven, in 5 the State of Connecticut, have invented certain new and useful Improvements in Curtain Rods, of which the following is a specification.

The invention relates to an improvement 10 in curtain rods, and more particularly to an improvement in curtain rods of the type in which a single, centrally-arranged curtain supporting member is mounted at its two ends on brackets provided with sockets for 15 detachably holding the curtain supporting member in place.

Curtain rods of this type have heretofore been so constructed that the bracket members have not been interchangeable, the left 20 hand bracket would serve only on the left hand end of the curtain rod and the right hand bracket would serve only on the right hand end of the curtain rod. This non-interchangeability of the bracket members 25 sometimes results in considerable inconvenience, especially when a curtain supporting member is supplied to a customer with either two left or two right hand brackets. The object of the present invention is 30 to obviate this inconvenience; and in accordance with this end it is proposed to make the brackets interchangeable, so that each will be equally adapted for use on the right hand end or the left hand end of the curtain rod. The invention is more fully described hereinafter and is particularly pointed out in the appended claims.

In the accompanying drawings illustrating the preferred form of the invention, Fig. 40 1 is a front elevation of the improved curtain rod, with a portion of the curtain supporting member broken away; Fig. 2 is a top plan of the parts shown in Fig. 1; Fig. 3 is a front elevation, partly in section, of one 45 of the brackets, with the reversible socket in the act of being turned to convert the bracket from a left hand to a right hand bracket; Fig. 4 is a view similar to Fig. 3, showing the socket fully turned and the 50 bracket converted into a right hand bracket; and Fig. 5 is a section, on an enlarged scale, taken along the line 5—5 of Fig. 1.

The improved curtain rod, as illustrated in the drawings, comprises a single flat centrally-arranged curtain supporting member

10, the ends of which are detachably mounted in brackets secured to the wall or window or door casement. Each bracket comprises a base portion 11 adapted to lie flat against the wall or casement and to be secured thereto by the screws 12, and an arm 13 projecting outwardly from the base 11 and then inwardly toward the adjacent end of the member 10.

On the free end of the offset inwardly projecting part 14 of each bracket is pivotally mounted a reversible socket 15. The socket is U-shaped, as clearly shown in Fig. 5, and the upper ends 16 of the sides of the socket are turned inwardly to function as a snap lock to detachably hold the ends of the curtain supporting member 10 in place. The sockets are held in place by means of the rivets 17. By means of this construction of the bracket and socket, each bracket may be 75 used interchangeably either as a left hand or as a right hand bracket.

The conversion of a bracket adapted to hold the left hand end of the curtain supporting member into a bracket adapted to hold the right hand end of the curtain supporting member is illustrated in Figs. 3 and 4. To convert the bracket from the left hand to a right hand bracket, it is simply necessary to turn the socket 15 through half 85 a revolution. To facilitate the turning of the socket the middle portion of the in-turned lips 16 are cut away at 18. While the socket is being turned, as shown in Fig. 3, the resiliency of the sides of the socket 90 permit the lips 16 to be forced apart by the part 14 of the bracket. When the socket has been turned, it brings the bottom 19 thereof in contact with the opposite edge of the part 14 of the bracket. Thus when the bracket, 95 shown in Figs. 3 and 4, served as a left hand bracket the bottom 19 of the socket was in contact with the edge 20 of the bracket part 14 and when the socket was turned the bottom 19 of the socket was brought into 100 contact with the edge 21 of the bracket part 14, as shown in Fig. 1.

When the brackets have been arranged so that one constitutes a left hand bracket and the other a right hand bracket, as shown in 105 Figs. 1 and 2, the curtain supporting member 10 is forced into place past the in-turned lips 16 of the sockets. To facilitate the insertion of the curtain supporting members 10 between the in-turned lips 16, the upper 110

edges of the latter are rounded at 22, as shown in Fig. 5.

Having thus described the invention what I claim as new is:—

5. A flat, elongated curtain rod comprising a curtain supporting member, and two brackets each of which is provided with a U-shaped reversible socket in which the adjacent end of the curtain supporting member is detachably held.

10. A curtain rod comprising a curtain supporting member and two brackets, each bracket being provided with a reversible socket consisting of a U-shaped piece pivoted on the free end of the bracket.

15. A curtain rod comprising a curtain supporting member and two brackets, each bracket being provided with a pivotally

20 mounted socket projecting beyond the end of the bracket to detachably receive the adjacent end of the curtain supporting member, each socket being reversible so as to receive the opposite end of the curtain rod when the bracket is placed at that end of the rod.

25 4. A curtain rod comprising a flat, elongated curtain supporting member and two brackets, each bracket being provided with a U-shaped socket pivoted to the free end of the bracket so as to project beyond the 30 end of the bracket and detachably receive the adjacent end of the curtain supporting member, said socket being reversible so that the position of its bracket may be reversed.

WILLIAM SCHAEFER.
